THE FOWLER & UNION HORSENAIL COMPANY, OF TONAWANDA, NEW YORK, A COR-
PORATION OF CONNECTICUT

MAIL HANDLING OR TRANSFER APPARATUS

Application filed March 10, 1930. Serial No. 434,549.

This invention relates to improvements in mail handling or transfer apparatus of the type for transferring mail between railroad trains, while moving, and wayside stations.

One of its objects is the provision of a simple, compact and rugged apparatus of this character which will facilitate the handling of mail between moving trains and stations, which is reliable and efficient in operation, and whose parts are so organized and arranged as to afford the transfer of the mail-bags from one point to the other with maximum safety and without liability of loss of mail matter or of injury to the mail-bags.

Another object of the invention is to so construct the mail handling portion or crane of the apparatus, which is applied to the car, that it can be compactly folded into the car and occupy a minimum of space and which can be swung into and out of the door-opening of the mail car with comparative ease.

Other features of the invention reside in certain novel improvements in the construction and arrangement of parts hereinafter described and particularly pointed out in the appended claims.

In the accompanying drawings:—

Figure 1 is a side elevation of the improved apparatus with its parts in operative relation, the car traveling toward the wayside station in readiness to deposit and pick up a mail bag. Figure 2 is an enlarged horizontal section taken in the plane of line 2—2, Figure 1. Figure 3 is a vertical section taken on line 3—3, Figure 2. Figure 4 is a transverse vertical section taken in the plane of line 4—4, Figure 3. Figure 5 is a horizontal section of one of the wayside station mail-bag wings or supports, taken on line 5—5, Figure 4. Figure 6 is a top plan view, with the cover plate removed, of the companion mail-bag support at the wayside station. Figure 7 is a similar view of the mail-bag wing or support on the car. Figure 8 is a vertical section taken on line 8—8,

Figure 2. Figure 9 is a fragmentary side view of the hinged end of the mail-bag wing on the car. Figure 10 is a top plan view, partly in section and similar to the left-hand portion of Figure 2, but showing the foldable 50 mail-bag support on the car in a partially retracted or projected position. Figure 11 is a horizontal section taken in the plane of line 11—11, Figure 8. Figure 12 is a detail side view showing the mail-bag arm of the 55 car swung out of the way when not in use.

Similar characters of reference indicate corresponding parts throughout the several views.

In its general organization, this improved 60 apparatus comprises means disposed along the track at a wayside station including collapsible upper and lower mail-delivery and mail receiving arms, and means mounted on the railway car for projection into and out 65 of the door-opening thereof and having mail-bag delivery and receiving elements thereon, whereby as the train travels past the wayside station, a mail bag may be deposited at the station and at the same time 70 one may be picked up.

In its preferred form, the mechanism at the wayside station for receiving and delivering the mail-bags, consists of a hollow post or column 10 adapted to be mounted on a 75 suitable platform disposed along the track and having slots or openings 11, 12 in its front and track side, these openings being arranged one above the other and in different vertical planes, as seen in Figure 3. The upper end of the column is closed by a suitable 80 cover 13. Mounted at the front side of the column are vertically-swinging, upper and lower mail-delivery and mail-receiving arms 14 and 15, respectively, which are disposed in vertically-spaced relation to permit the corresponding means on the railway car to pass horizontally between them, and which are spread in a horizontal direction sufficient 85 so there will be no interference between 90

the receiving and delivering operations. The upper arm 14 is fulcrumed adjacent its inner end on a horizontal pintle 16 journaled in appropriate bearings 17 positioned 5 within the column at the lower end of the upper slot 11, while the lower arm is fulcrumed on a pintle 18 journaled in bearings 19 likewise disposed within the column and adjacent the upper end of the lower slot 12.

10 At its outer end the lower arm 15 has a lateral extension or wing 20 arranged parallel to the track and preferably tapering opposite to the direction of travel of the train for receiving the suspension bail or rack 21 15 of the mail bag 22, the latter being detachably connected to the bail by snap fasteners 23. Mounted on opposite sides of this wing are horizontally-swinging detents or catch dogs 24 pivoted at 25 and constantly urged 20 to their outward or full line position shown in Figure 5 by a spring 26. The ends of the detents abut against corresponding shoulders 27 formed on the top side of the wings for limiting their outward movement and 25 they terminate adjacent such ends in hooks 28 with which the ends of the bail 21 are adapted to interlock for preventing forward displacement thereof from the wing. As seen in Figure 5, the end of the arm 15 terminates 30 in a lug or projection 29 disposed opposite the corresponding detent-hook 28 to prevent the bail slipping over the arm while adjacent its inner end said arm has a lateral lug or projection 30 facing the companion detent 35 hook, whereby the latter and said lug 30 together form a closure about the contiguous portion of the bail to prevent its displacement from the arm. After a mail-bag is deposited on this arm from a moving train, 40 it can be readily detached by contracting the detents and slipping the bail off the wing. To protect the detents and associated parts from the weather they may be covered by a plate 31 of the same contour of the wing 45 20 and secured thereto by screws or otherwise.

The companion upper arm 14, to which a mail bag is attached to be picked up by the train, has a lateral wing or extension 32 extending 50 in a direction opposite to that of the wing 20 and has mounted thereon similar spring-pressed contractible detents 33 whose outer edges are convexly curved to enable the mail-bag to be readily slipped on and off 55 the wing. These detents are likewise covered, with the exception of their bail-engaging edges, with a cover plate 34 and the latter has a pair of spaced ribs 35 thereon to raise the bail above the surface of said plate 60 and clear of its side edges to afford its free movement thereover as the bail slides off the wing when picked up by the moving train and allow for a slight tilting of the bail, if necessary, relative to the wing.

65 The upper and lower arms 14, 15 are so

hung from their respective fulcrums that the upper arm, in its inoperative position, assumes and is normally maintained in an upwardly swung position shown by dotted lines in Figure 4 and when a mail-bag is suspended 70 therefrom to be picked up by the train it automatically assumes and is held in the horizontal position shown by full lines, in said figure. The lower arm 15 normally assumes the horizontal position shown by full lines 75 in Figure 4 ready to receive a mail-bag to be deposited thereon by a passing train, and when a bag is so deposited, said arm is automatically swung to the pendant position shown by dotted lines in said figure. To this 80 end the arms are preferably counterweighted to normally retain them in their respective positions, the upper arm 14 being held in a substantially upright position by a weight 36 housed within the post 10 and suspended 85 from a cable 37 attached at its upper end to a sheave-quadrant 38 formed at the inner end of the arm. The lower arm 15 is held in a substantially horizontal position by a weight 39 likewise disposed within the post and suspended 90 from a cable 40 attached at its upper end to a sheave-quadrant 41 formed at the inner end of the arm, the sheave-quadrant having a stop lug 42 thereon which abuts 95 against an upwardly-facing shoulder 43 on the post for limiting the upward-swinging movement of the arm beyond its normal position for receiving a mail-bag from a passing train. The downward-swinging movement of the companion mail-delivery arm 14 100 is limited by its lower inner side abutting against the bottom edge of the corresponding post-opening 11. A catch 44 pivoted on the front side of the post below the fulcrum of the lower arm is adapted to interlock with 105 a lug 45 formed on the latter for holding it in its folded or pendant position against the post, as shown by dotted lines in Figure 4. By this arm suspension, the respective arms are automatically collapsible incident to the 110 reception and release of mail-bag loads, the mail-bag to be delivered on to a passing train holding the arm 14 in operative position until picked up by the train, and the mail-bag deposited from the train on to the lower arm 115 15 acting to swing the latter to its inoperative position and bring it within easy reach of the mail clerk to remove it therefrom.

The mechanism disposed within the railway car, for delivering and receiving the 120 mail-bags to and from the companion arms 15 and 14 mounted on the post 10 at the way-side station, is preferably constructed as follows:-

125 Mounted within the mail car 46 adjacent its door-opening 46^a is an upright post 47 on which is supported a foldable arm construction adapted to be projected through the door-opening and carrying mail-bag supports disposed to travel in a horizontal plane 130

between the upper and lower arms 14 and 15 at the wayside stations. This arm construction consists of a horizontally-swinging inner member or section 48 having bifurcated bearing portions 49 and 50 at its inner and outer ends, respectively, the inner bearing portions engaging the post 47 to revolve thereon. A collar 51 fixed on the post between the bifurcated bearings 49 serves to hold the arm-section 48 at the desired height. Disposed between the bifurcated outer bearing portions 50 is a horizontally-swinging joint member or knuckle 52 fixed on an upright shaft 53 journaled in said bearing portions, as seen in Figure 8 and fulcrumed at 54 on this knuckle is a vertically-swinging arm-section 55 which is held in a horizontal position by a ledge or stop lug 56 projecting forwardly from the lower side of said knuckle. By this construction, the outer arm-section 55 has a universal movement, being free to swing in both a vertical and horizontal plane so as to enable it to be compactly folded when not in use, as well as to effect its contraction sufficiently to pass into and out of the usual narrow door-opening of the mail car.

At its outer end the arm-section 55 has oppositely-facing lateral extensions or wings 57, 58 disposed in the same horizontal plane, the wing 57 converging forwardly or in the direction of travel of the train, as seen in Figure 2, for receiving a mail-bag from the delivery arm 14 at the wayside station, and the wing 58 serving to support a mail bag for delivering it on to the receiving arm 15 at such station. Mounted on opposite sides of the wing 57 are horizontally-swinging detents or catch dogs 59, similar to the detents 24 on the lower receiving arm 15, which are held yieldingly in their expanded position by a spring 60. Spring-pressed detents or catch dogs 61, similar to the detents 33 on the upper delivery arm 14, are likewise mounted on the companion wing 58. To protect these detents and associated parts from the weather, they may be covered by a plate 62. While this structure enables the supporting bails of the mail bags to be readily slipped on and off the respective wings, they effectually prevent their accidental displacement therefrom.

In its operative, projecting position from the mail car, shown in Figures 1 and 2, it is essential that the foldable arm construction 48, 52 and 55 be rigidly held against swinging horizontally out of place, and to this end simple and effective means are provided for interlocking the jointed parts against displacement relative to each other and to the car-post 47, such means being preferably constructed as follows:—

Mounted on the top side of the arm-section 48 and journaled in appropriate bearings applied thereto is a horizontal rock shaft 63 having crank-arms 64 adjacent its ends

arranged to actuate vertically-movable locking pins or bolts 65, 66 guided in corresponding openings in said arm-section and adapted for interlocking engagement with the collar 51 and knuckle 52, respectively. The locking bolt 65 is adapted to register with either one of two circumferentially-spaced recesses 67, 68 formed in the top side of the collar 51 for rigidly holding the arm-section 48 in one or the other of two predetermined positions. In the projected or extended position of the arm structure ready for receiving and delivering mail-bags, shown by full lines in Figures 1, 2 and 8 and by dotted lines in Figure 10, the bolt 65 engages the recess 67 which prevents movement of the arm-section about the post 47, while in the retracted or collapsed position of the structure, shown by dotted lines in Figure 10 and by dotted lines in Figure 2, the bolt 65 engages the recess 68 in the collar 51, these recesses being so spaced as to afford a movement of the arm structure about the post of over ninety degrees. The companion locking bolt 66 is adapted to register with either one of two circumferentially-spaced recesses 69, 70 formed in the top side of the knuckle 52 for rigidly holding the latter and its arm-section 55 in one or the other of two predetermined positions. In the projected position of the arm structure, the bolt 66 engages the recess 69 and in the collapsed position it engages the recess 70, such recesses being so spaced as to afford a relative movement of the arm-sections of less than ninety degrees. Co-operating stop lugs 71 and 72 are formed, respectively, on the outer end of the arm-section 48 and on the adjoining portion of the knuckle 52 to limit the unfolding action of the arm-sections and assist the locking bolt 66 in resisting accidental displacement of the outer arm-section out of its projected operative position.

As shown in Figures 8 and 9, the rock shaft 63 may be actuated by a hand lever 73 and a spring 74 applied to the shaft constantly urges the locking bolts 65, 66 downwardly into latched position. The free ends of the crank arms 64 may be rounded and be free to slide laterally of the bolts during their swinging movement in grooves 75 formed in the sides of the bolt-heads. A handle 76 projecting from the outer end of the arm section 48 is preferably provided for conveniently swinging the arm structure into and out of the mail car.

As before stated, this double-arm mounting on the car, which must be of a length to project the mail-receiving and delivering wings a suitable distance beyond the side of the car, permits the same to be sufficiently folded or fore-shortened to enable it to pass freely through the comparatively narrow door-opening 46. To facilitate this folding of the arm structure as it is swung into and

out of the car, we provide positive and reliable means for automatically effecting the relative folding and unfolding movements of the arm-sections 48 and 55 and for governing such movements at predetermined points in the path of travel of these parts. For this purpose, a tie or link connection is made between the fulcrum or post 47 about which the inner arm-section 48 swings and the fulcrum or shaft 53 about which the knuckle 52 of the outer arm-section 55 swings. Mounted on the car-post to turn thereon is a lever arm 77 and fixed on the shaft 53 to turn therewith is a lever arm 78, the free ends of these lever arms being pivotally connected by a link or tie bar 79. By this construction, as the arm structure is swung into the car from its projected position, this tie connection causes the outer arm-section to be folded inwardly toward the inner arm-section, such outer arm-section swinging at a faster rate of travel about its fulcrum 53 than that of the inner arm-section to permit the former to reach a position to swing clear of the rear edge of the door-opening. In this position of the parts, shown by dotted lines in Figure 2 and by full lines in Figure 10, the locking bolt 66 is in engagement with the knuckle-recess 70, but the companion locking bolt 65 has not as yet interlocked with the collar 51. However, upon swinging the arm-structure further inwardly to the dotted line position depicted at the upper portions of Figures 2 and 10, the bolt 65 will snap into interlocking engagement with the collar-recess 68, wherein the arm structure assumes a position cross-wise of the car and the outer arm section 55 is then swung upwardly about its fulcrum 54 and held in a substantially upright position by a suitable catch 80 attached to a supporting bar 81, whereby the whole structure is compactly folded and out of the way when not in use, as seen in Figure 12. When it is desired to project the arm structure out of the car for delivering and receiving mail, the steps just described for retracting it into the car are merely reversed.

We claim as our invention:—

1. A mail handling apparatus of the character described, comprising an arm for detachably receiving a mail-bag carrier-bail, contractible detents mounted on said arm and with which said bail is adapted to interlock to prevent displacement thereof lengthwise of the arm, and a lug on the latter adjoining one of said detents and forming with the same a closure about the contiguous portion of the bail.

2. A mail handling apparatus of the character described, comprising a support, a sectional arm fulcrumed on said support for movement as a unit in a horizontal plane and the sections of which are fulcrumed to each other to fold and unfold in the same plane,

and mail-bag receiving means applied to the free end of the arm.

3. A mail handling apparatus of the character described, comprising a support, a sectional arm fulcrumed on said support for movement as a unit in a horizontal plane and the sections of which are fulcrumed to each other to fold and unfold in the same plane, means for latching said arm-sections in predetermined positions relative to each other, and mail-bag receiving means applied to the free end of the arm.

4. A mail handling apparatus of the character described, comprising a support, a horizontally-swinging arm-structure fulcrumed on said support and consisting of horizontally-foldable sections, mail-bag receiving means applied to the outer arm-section, and means for latching the arm-sections in an extended or unfolded position and in a retracted or folded position.

5. A mail handling apparatus of the character described, comprising a support, a horizontally-swinging arm-structure fulcrumed on said support and consisting of horizontally-foldable sections, mail-bag receiving means applied to the outer arm-section, means for latching the arm-sections in an extended or unfolded position and in a retracted or folded position, and means for automatically governing the folding and unfolding movements of the arm-sections when the arm-structure is swung about said support.

6. In a mail bag transfer apparatus for railway cars, the combination of a supporting post, a horizontally-swinging arm-structure fulcrumed on said post and consisting of horizontally-foldable sections projectible through the car-opening to an extended operative position and retractible through said opening to a collapsed inoperative position, mail-bag receiving means applied to the outer end of the arm structure, and means for effecting a relative folding of the arm-sections during the swinging movement of the arm-structure through the door-opening.

7. In a mail bag transfer apparatus for railway cars, the combination of a supporting post, a horizontally-swinging arm-structure fulcrumed on said post and consisting of horizontally-foldable sections projectible through the car-opening to an extended operative position and retractible through said opening to a collapsed inoperative position, mail-bag receiving means applied to the outer end of the arm structure, and a link connection between the supporting post and the outer arm-section for effecting a folding of the latter toward its companion inner arm-section as the arm-structure is swung as a unit into and out of the car through its door-opening.

8. In a mail-bag transfer apparatus for railway cars, the combination of a supporting post, a horizontally-swinging arm structure fulcrumed on said post and consisting of hori-

zontally-foldable sections projectible through the car-opening to an extended operative position and retractible through said opening to a collapsed inoperative position, mail-bag receiving means applied to the outer end of the arm-structure, means for effecting a relative folding of the arm-section during the swinging movement of the arm structure through the door-opening, and latching means for locking the arm-structure against movement as a unit out of its projected and retracted positions.

9. In a mail-bag transfer apparatus for railway cars, the combination of a supporting post, a horizontally-swinging arm structure fulcrumed on said post and consisting of horizontally-foldable sections projectible through the car-opening to an extended operative position and retractible through said opening to a collapsed inoperative position, mail-bag receiving means applied to the outer end of the arm-structure, means for effecting a relative folding of the arm-sections during the swinging movement of the arm-structure through the door-opening, latching means for locking the arm-structure against movement as a unit out of its projected and retracted positions, and latching means for locking the arm-sections in their folded and unfolded positions.

10. In a mail-bag transfer apparatus for railway cars, the combination of a supporting post, a horizontally-swinging arm structure fulcrumed on said post and consisting of horizontally-foldable sections projectible through the car-opening to an extended operative position and retractible through said opening to a collapsed inoperative position, mail-bag receiving means applied to the outer end of the arm-structure, a collar applied to said post and on which the inner end of the arm-structure is adapted to rest, and latch bolts applied to the inner arm-section and disposed for interlocking engagement with said collar and the adjoining inner end of the outer arm-section, respectively.

11. In a mail-bag transfer apparatus for railway cars, the combination of a supporting post, a horizontally-swinging arm-structure fulcrumed on said post and consisting of horizontally-foldable sections projectible through the car-opening to an extended operative position and retractible through said opening to a collapsed inoperative position, mail-bag receiving means applied to the outer end of the arm-structure, a collar applied to said post and on which the inner end of the arm structure is adapted to rest, said collar having a plurality of circumferentially-spaced openings therein, and the inner end of the outer arm-section having similar openings therein, an actuating member applied to the inner arm-section, and latch bolts operatively connected to said actuating member and disposed for interlocking engage-

ment with one or another of the corresponding openings in said collar and said inner arm-section, respectively.

12. In a mail bag transfer apparatus for railway cars, the combination of a supporting post, a pair of horizontally-foldable arms pivotally joined at their opposing ends, the inner arm being fulcrumed for horizontally-swinging movement on said post and the outer arm being adapted to support a mail-bag, the pivot joining said arms being journaled in the inner arm and fixed to the outer arm, and motion transmitting means connecting said pivot with the supporting post, whereby the outer arm is foldable relatively to the inner arm as the latter is swung about said post to bring the arms to an extended position exterior of the car or to a retracted position interior of the car.

13. In a mail-bag transfer apparatus for railway cars, the combination of a supporting post, a pair of horizontally-foldable arms pivotally joined at their opposing ends, the inner arm being fulcrumed for horizontally-swinging movement on said post and the outer arm being adapted to support a mail-bag, the pivot joining said arms being journaled in the inner arm and fixed to the outer arm, horizontally-movable lever fulcrumed on the supporting post, a lever fixed on said pivot, and a link pivotally connected at its ends to said levers.

14. In a mail-bag transfer apparatus for railway cars, the combination of a supporting post, a pair of horizontally-foldable arms pivotally joined at their opposing ends, the inner arm being fulcrumed for horizontally-swinging movement on said post and the outer arm being adapted to support a mail-bag, the pivot joining said arms being journaled in the inner arm and fixed to the outer arm, motion transmitting means connecting said pivot with the supporting post, whereby the outer arm is foldable relatively to the inner arm as the latter is swung about said post to bring the arms to an extended position exterior of the car or to a retracted position interior of the car, and means for latching said arms in a predetermined position relative to each other and in their extended and retracted positions, respectively.

15. In a mail bag transfer apparatus for railway cars, the combination of a supporting post having a collar thereon, a horizontally-swinging arm structure fulcrumed on said post above its collar and consisting of an inner arm-section mounted on the latter, a knuckle member fulcrumed at the outer end of said arm-section for movement in a horizontal plane, and an outer arm-section adapted to support a mail-bag and fulcrumed on said knuckle member for vertically-swinging movement, a rock shaft journaled on the inner arm-section, and latch bolts guided in the opposite ends of the latter and opera-

tively connected to said rock shaft, one of said bolts being disposed to interlock with the post-collar to hold the arm-structure in any one of a plurality of predetermined positions, and the other of said bolts being disposed to interlock with the knuckle member to hold the latter in any one of a plurality of positions relative to said inner arm-section.
